UNITED STATES PATENT OFFICE.

MILDRED COALE ALLEN, OF HIGHLAND PARK, ILLINOIS.

CHILD'S GARMENT.

Application filed July 27, 1922. Serial No. 577,900.

This invention relates to children's garments, and has for its object to provide a new and improved garment particularly adapted as a night garment. The invention is illustrated in the accompanying drawings wherein—

Fig. 1 is a view of the material after being cut and before being folded into shape showing one form of garment;

10 Fig. 2 is a view similar to Fig. 1 after the parts have been folded;

Figs. 3 and 4 show a modified construction where the front and back are made separate and sewed together;

15 Fig. 5 is a view showing a further modification;

Fig. 6 is a perspective view showing a method of fastening the top ends of the front portions of the garment.

20 Like numerals refer to like parts throughout the several figures.

The garment may be made in one or more pieces as desired. In forming the garment, instead of having the sleeves extend laterally from the garment as is the ordinary form, I arrange the sleeves so that they extend perpendicularly, that is to say, so that they are in alignment longitudinally with the garment, such sleeves extending from the upper end of the garment.

Referring now to the drawings I have shown in Fig. 1, one form of garment made out of a single piece of any suitable material. In this construction the body 1 of the garment is formed integral with the sleeves 2 and 3, the material for said sleeves projecting from the upper edge of the body portion and being in a plane longitudinal with the body portion. The material is then folded over along the lines 4 and 5, and the edges of the sleeves sewn or otherwise fastened together, the garment then being as illustrated in Fig. 2. The particular process of making the garment as shown in Figs. 1 and 2 is to cut away the upper corners as shown in Fig. 1 so as to have the faces 3^a and 2^a and then cut away at the upper end a central part 3^a so as to leave the faces 3^b and 3^c, and then fold the parts over on the lines 4 and 5 and then fasten the inner longitudinally extending meeting edges of the cut away portions by sewing or otherwise the edge of the cut away portion 2^a with the edge 3^c and also fastening by sewing or otherwise the edge 3^a with the edge 3^b, this forming the garment.

Instead of having the sleeves integral with the garment, they may be separate therefrom. The edges of the garment may be fastened together by any suitable fastening means. For purposes of illustration I have shown these edges as fastened by suitable tapes 7 attached thereto having loose ends which may be joined.

In Figs. 3 and 4 I have shown a further modification where the front of the garment is made of a piece 1^a and the back of a piece 1^b, and these two pieces are sewed or otherwise fastened together to form a garment.

70 In Fig. 5 I have shown a further modification, illustrating a closed garment. The ends of the sleeves 2 and 3 are closed in any desired manner. For purposes of illustration I have shown these ends as being closed by the stitching 10.

The bottom portion after the child is in, may be folded up and may be fastened in its folded position by any suitable fastening means, such for example as safety pins 80 11. This forms a closed bag and in addition to being a warm garment, prevents the child from sucking its finger or thumb.

85 The portions which form the front of the garment may be fastened to the back in any desired manner. I prefer, however, to fasten the front portions in such a manner as to throw the bottom parts thereof toward each other. One way of doing this is by lapping a portion of the upper end of the front portion over the back, and then sewing in this position, as shown for example in Fig. 6. In this figure, the overlapping portion 12 which is triangular in shape is produced by pulling the upper end of the front portion upwardly, and this swings the lower ends toward each other and makes the angle at 12^a, that is the angle between the edge 14 of the front portion and the top neck portion of the back, that is to say an acute angle instead of a right angle. In practice I may make this angle such that the lower ends of the front portions will overlap as illustrated in Fig. 2, leaving at the top a space 15 between them which forms the neck opening of the garment. This construction also strengthens the seam.

100 It will further be seen that the garment can be easily and quickly and cheaply made, and a garment made for an infant will not 110 be outgrown until the child is about four years of age.

In the event that the child sleeps on its stomach, the corners of the front part of the garment can be turned back to insure dryness of the garment in case of bed wetting, and still make the necessary protection to the back, arms and shoulders of the child. The garment may be made out of any suitable material, and the proportions and arrangement varied to suit the conditions presented.

I have described in detail a particular construction embodying the invention but it is of course evident that the parts may be varied in many particulars without departing from the spirit of the invention as embodied in the claims hereto appended, and I therefore do not limit myself to the particular construction shown.

I claim:

- 20 1. A child's garment comprising a body portion, sleeves connected with the top of the body portion and extending therefrom substantially in longitudinal alignment with the body portion, said sleeves being formed and extending upward from the shoulder portion of the garment.

2. The process of making a child's garment from a piece of material which consists in removing a portion of the material from each of the two upper corners, and a piece of material from the center portion of the upper end so as to leave two upwardly projecting parts at the upper end, and folding the sides of the piece of material inwardly and fastening the inner longitudinally extending meeting edges of said cut away portions together to form the garment.

3. A garment comprising a body portion, projecting sleeve portions at the upper end of the body portion substantially in longitudinal alignment therewith, the outer sections of the body portion and the sleeve portions being bent so as to overlap the adjacent portions, the free longitudinally extending edges of the overlapping sleeve portions being connected together, and the adjacent edges of the overlapping sections of the body portion being connected together.

Signed at Chicago county of Cook and State of Illinois, this 24th day of July, 1922.

MILDRED COALE ALLEN.
